SHAKER CHUTE CONSTRUCTION

Donald U. Rich, Teaneck, N. J., assignor to American Car and Foundry Company, New York, N. Y., a corporation of New Jersey

Application December 4, 1933, Serial No. 700,856

15 Claims. (Cl. 198—220)

This invention relates to reciprocating conveyors of the trough type for conveying material, such as coal or the like, from one place to another, and known in the art generally as shaker chutes.

5 The primary object of this invention is the provision of a new and improved shaker chute construction.

Another object of this invention is the provision of a shaker chute construction embodying 10 a ball frame and a trough supported thereby in such a manner as to permit independent rocking thereof relative to the ball frame.

Still another object of this invention is the provision of a shaker chute construction embodying 15 a ball frame and a trough supported thereby through the medium of a connecting element which is interfittingly supported on the ball frame.

A further object of this invention is the provision 20 of a new and improved ball frame for shaker chutes.

Devices of the character shown and described, while in service, are not always arranged in a true horizontal plane. This is due to inequalities 25 in the mine floor, and because of such a condition it is necessary that ball frames be of such a character as to permit rocking movement of the trough relative to the ball frame. In view of this, another object of this invention is the provision 30 of a ball frame for shaker chutes in which a trough is connected thereto for reciprocation, the connection being effected through the medium of a reciprocable ball frame member and a connecting element rigidly secured to the trough; said member and element being interfitted 35 through complementary formed portions in such a manner as to permit the trough to have substantially a rocking movement relative to the ball frame, and relative to said reciprocable ball frame member.

Still another object of this invention is the provision of a new and improved body member for ball frames of shaker chutes.

A still further object of this invention is the provision 45 of a shaker chute construction comprising a reciprocable body member, a trough and means connecting the trough to the body member, the body member and connecting element being so formed that a single point support is created.

Other objects and advantages of this invention will be apparent from the following description taken in conjunction with the accompanying drawings, in which

55 Figure 1 is a top plan view of one form of the

present invention, certain parts being broken away to disclose other parts in section;

Fig. 2 is a partial side elevation of the construction shown in Figure 1, a certain part of said figure being taken on the line 2—2, Figure 1; 60

Fig. 3 is an end view of the ball frame shown in Figure 1, certain parts thereof being shown in section on the line 3—3, Figure 1;

Fig. 4 is a top plan view of the connecting element secured to the trough; 65

Fig. 5 is a view, partly in section, of the ball frame body member;

Fig. 6 is a sectional view of the ball frame body member, the view being taken on the line 6—6, Fig. 1; 70

Fig. 7 is a fragmentary view, in section, showing one of the raceways with the anti-friction elements therein, the view also showing the central spacer for said anti-friction elements;

Fig. 8 is an enlarged sectional view through one 75 of the raceways, the view being taken on the line 8—8, Fig. 9;

Fig. 9 is a sectional view on the line 9—9, Fig. 8;

Fig. 10 is an enlarged fragmentary sectional 80 view showing the assembly of the T and the ball frame body member;

Fig. 11 is a sectional view on the line 11—11, Fig. 3, the view also showing in dotted lines the T in shifted position; 85

Fig. 12 is a sectional view taken on the line 12—12, Fig. 13;

Fig. 13 is a view, partly in elevation and partly in section, of a modified form of ball frame body member, the view also showing a T associated 90 therewith and being taken on the line 13—13, Fig. 14;

Fig. 14 is a top plan view of a modified form of ball frame body member, the view also showing a portion of a T associated therewith; 95

Fig. 15 is a sectional view of another modified form of the invention, the view being taken on the line 15—15, Fig. 16;

Fig. 16 is a sectional view of the modified form of the invention shown in section in Fig. 15, the view being taken on the line 16—16, Fig. 17; 100

Fig. 17 is a partial top plan view of the modified form of the invention shown in Figs. 15 and 16, the view also showing a T associated with the ball frame body member; 105

Fig. 18 is a sectional view showing still another modified form of the invention, the view being taken on the line 18—18, Fig. 19; and

Fig. 19 is a fragmentary top plan view of the modified form shown in Fig. 18. 110

Referring now more particularly to the drawings, in which similar characters of reference designate similar parts in the several views, and with specific reference to Figs. 1 to 3, inclusive, 5 the ball frame of the present invention comprises a base frame A and a reciprocable body member B with which a trough section C of a conveyor is connected by means of a connecting element D.

10 The base frame A, in the instance shown, comprises spaced channel shaped supporting members 2, connected by upwardly extending inwardly facing angles 4 which constitute guideways or track members for suitable anti-friction elements 15 such as the balls 6 which are adapted to roll on the members 4 and which support the body member B as presently to be described.

The body member B comprises a metal plate 8, the marginal edge portions of which are downwardly flanged to provide side and end stiffening elements 10 and 12, respectively, the end flanges 12 depending vertically downwardly from the upper surface of the plate and having angle members 16 secured thereto by fasteners 18, said members 16 constituting upper track members. As more clearly shown in Fig. 3, the horizontal flanges of the angles 16 are so arranged as to rest upon the anti-friction elements 6 and to extend beneath in-turned flanges 19 formed on the upper 30 edge portions of the vertical legs of the angles 4. The fasteners 18 also secure a spacer 20 (see Fig. 7) which, viewed in plan, is substantially channel shaped with the legs 22 thereof projecting to serve as stop elements for retaining 35 the balls 6 in spaced relation and for confining the balls to a limited rolling movement. The before-mentioned fasteners 18 also serve to secure to the inner surfaces of the flanges 12 of the body member B a stop element 24 which is adapted to contact with the supporting elements 2 and limit reciprocatory movement of said body member.

40 As clearly shown in Figs. 1 to 3 inclusive, the end portions of the plate 8 slope gradually downwardly as at 26 toward the end flanges 12. It can also be seen that, in general, the plate 8 is curved transversely (see Fig. 2). Between the sloping end portions 26, spaced arcuate depressions or recesses 28 are formed in the plate on opposite sides, 45 lengthwise of the plate, of a pair of aligned recesses 30 arranged in spaced relation transversely of the plate 8 and approximately midway between the ends thereof. As will be apparent from the description to follow, the depressions 28 constitute 50 bearing portions for the connecting element D. Along opposite sides of the recesses 28 and extending lengthwise of the plate between the recesses 30 and the sloping end portions 26 are shoulders 32 which obviously serve to enlarge the recesses 28 or, in other words, to increase the effective 55 bearing areas thereof. These shoulders are shown clearly in elevation in Fig. 5 and in section in Fig. 6.

60 Formed lengthwise in the plate approximately midway between the side edges thereof is a slot 34 which cuts through the bearing portions or recesses 28, as shown more clearly in Figs. 1, 10 and 11, and which serves to position the connecting element D, the latter, in the instance shown, 65 comprising a T having a head portion 36 and a leg 38 arranged in the slot 34.

The T D is shaped to the form shown clearly 70 in Figs. 4, 10 and 11, the head portion 36 of said T being pressed or otherwise suitably formed in 75 such a manner as to provide bearing elements 40

spaced longitudinally of the T and complemental in form to the recesses 28; said bearing elements 40 being adapted to seat in the bearing portions 28, the resulting assembly therefore being one in which the connecting element D and the body member B are inter-fitted for service, the construction constituting a single point support, which, in the instance shown, is arranged adjacent the leg 38 of the T, as clearly shown in Figure 10.

80 As more clearly shown in Fig. 4, the head portion 36 of the T D is provided with spaced pairs of openings 42, three pairs being shown in the drawings, which openings take rivets 44 (see Fig. 3) to connect the T to the trough. The openings 42 are so arranged that the heads of the center row of rivets will be arranged at the center recesses 30, said recesses providing an arrangement whereby the rivet heads do not contact or otherwise frictionally engage the plate 8. Due to the downward slope 26 at the end portions of the plate 8 it can be seen that clearance sufficient to prevent frictional engagement of the heads of the outer rows of rivets with the plate 8 is provided and further, said downwardly sloping portions provide a construction which permits transverse rocking or tilting of the trough and its associated T relative to the body member B.

85 In service, a number of trough sections C are connected end to end and several ball frames are 105 provided for supporting these connected troughs. Due to inequalities in the mine floor the assembled units are obviously not always in the same horizontal plane and this necessitates the provision of a ball frame in which rocking or tilting movement of the trough directly associated therewith should be permitted. In the instance shown in Figs. 1 to 4, 10 and 11, rocking movement of the trough longitudinally relative to the ball frame 110 body member B is permitted by the complementally inter-fitted portions of the connecting member D and body member B as clearly shown in full lines in Fig. 10 and in dotted lines in Fig. 11, said last named figure showing in full lines the connecting element D in its normal position. It will also be apparent that both longitudinal and transverse rocking or tilting of the trough is permitted without frictional contact of the rivets 42 and the body member 8.

90 In the form of the invention shown in Figs. 12 125 to 14 inclusive, parts similar to those shown in Figs. 1 to 4, 10 and 11 are indicated by corresponding and similar reference characters. Fig. 14 shows the body member B as provided with a pair of adjacently arranged substantially circular 130 depressed bearing portions 46 arranged in spaced relation longitudinally or lengthwise of the body member and receiving complementally formed bearings 48 pressed in the connecting member or T D, the T being thus inter-fitted with the body member B.

95 Figs. 15 to 17 inclusive, disclose another modification of the invention wherein it can be seen that the body member B is provided with spaced pairs of depressed bearing portions 50 arranged 140 on opposite sides of the slot 34, these bearing portions 50 being adapted to receive complementally formed bearings 52 formed in spaced relation in the head of the T D as shown clearly in Fig. 15. The bearing portions 50 of Figs. 15 to 17 inclusive, are elongated and are arranged in spaced relation lengthwise of the body member B.

100 Figs. 18 and 19 show a still further modification of the present invention in which the body member B is provided with a plurality of sub- 130

stantially circular depressed bearing portions 54 arranged in rows along opposite sides of the slot 34 in the body member and said bearing portions 54 are adapted to receive complementally formed bearing elements 56 formed in the head portion of the T D.

Figs. 8 and 9 show the body member B and its associated track member 16 in shifted position and it can be seen that the spacer 20 has caused one of the anti-friction elements 6 to be shifted to substantially the limit of its rolling movement toward the right as viewed in said Figs. 8 and 9. For limiting the rolling movement of the anti-friction elements 6 in the guideway defined by members 4 and 16 an abutment 58 extends into the guideway at a point substantially midway between the ends of the member 4; said abutment being preferably secured to the attaching flange 60 of the track member 4. During shifting movement of the body member B and its associated track member 16 to the right as viewed in Figs. 8 and 9, it can be seen that the spacer element 20 will positively move one of the anti-friction elements 6 to the right while movement of the opposite element 6 to the right may be effected by the down-turned flange 62 so that upon reversal of movement of the track member 16 and the body member B, should the anti-friction elements 6 be inclined to stick they are positively moved by the spacer 20 and the opposite flange 62. The provision of the spacer 20 and the abutment 58 provides a construction in which the anti-friction elements 6 are always maintained in spaced relation which thus prevents any tendency of the body member B and its track member 16 to become "cocked" or arranged relative to the track member 4 as to bind thereagainst in service.

From the above description it is believed that the construction and operation of the ball frame of the present invention will be fully apparent to those skilled in the art. The drawings herein illustrate certain embodiments of the invention but it is to be understood that they are for illustrative purposes only and various changes in the form and proportions of the construction may be made within the scope of the appended claims without departing from the spirit of the invention.

What is claimed is:

50 1. In a shaker chute, a trough, a connecting element secured to the trough and provided with projecting bearing elements arranged in longitudinally spaced relation with respect to said connecting element, and a ball frame having a reciprocable body member with which said connecting element is connected, said body member being provided with depressed bearing portions arranged in longitudinally spaced relation and receiving said bearing elements.

60 2. In a shaker chute, a trough, a ball frame having a reciprocable body member, and a connecting element secured to the trough and extended into the body member, said body member and connecting element having complementally formed interfitted portions alined transversely relative to the body member, said interfitted portions being so formed and arranged as to permit independent rocking movement of the trough.

70 3. A ball frame for use with shaker chutes comprising a reciprocably mounted body member having adjacently arranged depressed bearing portions formed in its upper surface adapted to receive bearing members of a shaker chute in said depressed portions.

75 4. A ball frame for use with shaker chutes

comprising a reciprocably supported body member having adjacently arranged depressed bearing portions formed in longitudinally spaced relation in its upper surface and each adapted to receive a bearing member of a shaker chute therein.

5. In a ball frame for shaker chutes, a base frame comprising spaced track-ways, anti-friction elements movably supported on the track-ways, and a trough-supporting body member reciprocably mounted on said anti-friction elements and comprising a plate extending between the trackways and having adjacently arranged depressed bearing portions formed therein and each adapted to receive a bearing member of a shaker chute.

6. In a ball frame for shaker chutes, a base frame comprising spaced track-ways, anti-friction elements movably supported on the track-ways, and a trough-supporting body member reciprocably mounted on said anti-friction elements and comprising a plate having flanges depending from the end portions thereof, the end portions of said plate sloping gradually upward from the flanges, and depressed bearing portions formed in said plate between said upwardly sloping portions and arranged in longitudinally spaced relation, said depressed bearing portions each being adapted to receive a bearing member of a shaker chute.

7. In a shaker chute, a trough, a connecting element secured to the trough and provided with bearing elements, and a ball frame having a reciprocable body member into which said connecting element extends, said body member having integrally formed bearing portions in which the bearing elements are seated, said bearing elements and bearing portions being alined transversely of the body member and so arranged as to permit longitudinal rocking movement of the trough independently of the body member.

8. In a shaker chute, a trough, a connecting element secured to the trough and including a depending portion, said connecting element having projecting bearing elements formed therewith, and a ball frame comprising spaced tracks and a reciprocable body member extending between the tracks and into which said depending portion projects, said body member having depressed bearing portions receiving said bearing elements.

9. In a shaker chute, a trough, a connecting element secured to the trough and including a depending portion, said connecting element having projecting bearing elements formed therewith adjacent the depending portion, and a ball frame comprising spaced tracks and a reciprocable body member extending between the tracks and into which said depending portion projects, said body member having depressed bearing portions receiving said bearing elements.

10. In a shaker chute, a trough, a connecting element secured to the trough and including a depending portion, said connecting element being provided with projecting bearing elements formed adjacent the depending portion and arranged in longitudinally spaced relation, and a ball frame having a reciprocable body member into which said depending portion extends, said body member having a depressed bearing portion receiving said bearing elements.

11. In a shaker chute, a reciprocable body member having depressed bearing portions formed therein, a trough, a connecting element having bearing elements formed therewith and so arranged as to cooperate with the bearing por-

tions in such a manner as to permit independent rocking movement thereof relative to the body member, and fasteners securing the connecting element to the trough, the cooperating bearing portions and bearing elements serving to space the fasteners from the body member in all positions of the trough.

12. In a shaker chute, a reciprocable body member, a trough, a connecting element, and fasteners securing the connecting element to the trough, said connecting element having downwardly projecting bearing elements resting on the body member and spacing the fasteners from the body member whereby to maintain said fasteners out of frictional engagement with said body member.

13. In a shaker chute, a trough, a ball frame having spaced tracks, a reciprocable body member extending between said tracks, and a connecting element secured to said trough and ex-

tended into the body member, said body member and connecting element having complementary formed interfitted bearing portions so arranged as to permit independent rocking movement of the trough.

14. In a shaker chute, a trough, a connecting element secured to the trough formed with a downwardly extending bearing portion, a ball frame including spaced tracks, and a reciprocable body member extending between said tracks having a complementary seat for said bearing portion.

15. An article of manufacture comprising a shaker chute trough, a T-shaped support secured thereto, downwardly extending bearing elements projecting from the head of said support, and a complementary bearing member interfittingly cooperating with said bearing elements.
